INVENTOR:
MARTIN MADSEN,
BY
FRED W. JONES
ATTORNEY.

UNITED STATES PATENT OFFICE.

MARTIN MADSEN, OF MONTEREY PARK, CALIFORNIA.

SUCKER-ROD CLAMP.

Application filed February 3, 1925. Serial No. 6,612.

This invention relates to oil pumping equipment, and it relates particularly to a unique polish rod clamp.

In the oil producing industry, oil is usually pumped from a well by means of a pump plunger situated in a pump barrel at the bottom of a well. A string of sucker rods extends upwardly through a pump tubing to which the pump barrel is secured, to the surface of the ground. At the upper end of a string of sucker rods, there is attached a polish rod which extends through a stuffing box placed at the upper end of the pump tubing of the well. The polish rod is connected with a walking beam which reciprocates the pump plunger by means of the string of sucker rods in a manner to elevate oil to the surface of the ground.

As a means for joining the polish rod with the walking beam, it is common to use a polish rod clamp which is secured to the upper end of the polish rod. Reins are extended from the polish rod clamp and connect to the walking beam. It is to polish rod clamps of this character that my invention relates.

It is an object of my invention to provide a polish rod clamp of this character which will have a great gripping force. I accomplish this by providing the clamp in the form of a pair of coacting clamp members which are pivotally secured together, and which provide a longitudinal channel through which the polish rod extends. Arranged in this channel is a gripping member which is adapted to be forced into gripping engagement with the polish rod by the clamp members, and the grippers are so designed as to greatly magnify an initial clamping force as will be thoroughly described hereinafter.

It is also an object of my invention to provide a polish rod clamp of this character in which all the parts thereof are tied together. This eliminates the possibility of misplacing the parts and adds to the convenience of installation and removing of the polish rod clamp, due to the fact that the various parts thereof are always in their proper positions.

It is a further object of my invention to provide a polish rod clamp of the character mentioned which is superior to other clamps inasmuch as it will be of small cost, rugged construction and will be easy to manipulate.

Other objects and the specific advantages of my invention will be made evident hereinafter.

Referring to the drawing which is for illustrative purposes only,

Fig. 1 is a diagrammatic view illustrating the utility of my invention.

Fig. 2 is a plan view of a polish rod clamp embodying the features of my invention, this view being taken substantially on the line 2-2 of Fig. 1.

Fig. 3 is a section taken as indicated by the line 3-3 of Fig. 2.

Fig. 4 is an elevational view taken substantially as indicated by the arrow 4 of Fig. 2.

With reference to Fig. 1 of the drawings, I show a polish rod 11 extending through a stuffing box 12 of a pump tubing 13. A polish rod clamp 15 which embodies the features of my invention is shown as secured at the upper end of the polish rod 12. Extending from the clamp 15 is a pair of reins 16 which extends up over a walking beam 18 which saddles on a Samson post 19. A reciprocation of the walking beam 18 reciprocates the polish rod 11 through the reins 16 and my polish rod clamp 15 in a manner to reciprocate the pump plunger, not shown, thus pumping oil upwardly through the pump tubing 13 and through a piping 20. The polish rod clamp 15 is clearly shown in detail in Figs. 2 to 4, inclusive.

My invention provides a body 26 composed of a pair of clamp members 27. These clamp members 27 are provided with formations 28 which are disposed as shown in Figs. 2 and 3, through which formations 28 there extends a hinge rod 29. This hinge rod 29 hinges the clamp members 27 together. The adjacent faces of each of the hinge members 27 have longitudinally extending V-shaped depressions 30. The V-shaped depressions 30 cooperate to provide a longitudinal channel 32 which opens at a point opposite to the hinging of the members 27. The polish rod 11 extends through the channel 32 engaging with faces 34 of the members 27, these faces being at the bottom of the channel 32.

A gripper 36 is placed in the channel 32 having a longitudinal groove 37 which provides engaging faces 38. The gripper 36 is provided with back wedge faces 39. These wedge faces 39 are at 90° with respect to each other, and each of these faces 39 is at 45° with respect to the direction of motion of the gripper 36 as will be described. Con-

5 convex engagement formations 42 are provided by each of the clamp members 27, these convex engagement formations 42 being formed in the depressions 30 and being arranged for engagement with the wedge faces 39 of the gripper 36.

An opening 44 is provided in a tail 45 which extends from the rear portion of the gripper 36. Extending through the opening 10 44 is a tongue 46, this tongue 46 extending from one of the clamp members 27. A cotter key 47 or its equivalent is extended through a projecting end of the tongue 46, thus preventing the removal of the gripper 15 36 from the tongue 46. As clearly shown in Fig. 3, the opening 44 is somewhat wider than the tongue 46; therefore, the gripper 36 is free to move transversely with respect to the body 26.

20 Bolts 50 are pivotally secured to one of the clamp members 27 by means of a pin 51 which extends through lugs 52 of this clamp member 27 and through bosses 54 of the bolts 50. The other of the clamp members 25 27 is provided with a flange 56 having slots 57 therein, through which the bolts 50 extend when they are in positions shown in the drawings. A nut 58 is threaded on an extending end 59 of each of the bolts 50. 30 Trunnions 61 extend from each of the clamp members 27 on which trunnions 61, as shown in Fig. 1, are pivoted bearing members 62 which form a part of the reins 16.

By advancing the nuts 58 on the bolts 50, 35 the clamp members 27 are hingeably moved relative to each other, thus clamping the gripper 36 against the polish rod 11. When the clamp members 27 are clamped together, the engagement formations 42 are moved inwardly against the wedge faces 39 of the gripper 36. This forces the gripper member inwardly in a transverse or radial direction against the polish rod 11, tightly gripping this polish rod 11 between the 40 faces 39 of the gripper 36 and the faces 34 of the bottom of the channel 32.

The gripping force applied by my polish rod clamp is exceedingly great. A considerable force may be applied to the clamp member 27 by the bolts 50 and the nuts 58 which comprise a mechanical screw. The leverage applied to the gripper member 36 by the clamp members 27 is substantially double the force applied by the bolts and nuts 50 and 58. As clearly shown in Fig. 2, this embodiment shows substantially a two to one lever arm proposition. By employing a moving wedge arrangement of the character shown, the force applied to the polish 55 rod 11 by the gripper member 36 is also substantially doubled in this modification of my invention.

The parts of the polish rod clamp 15 are all tied together so that it will be impossible 60 to lose or misplace any of them. The grip-

per 36 is movably retained in place by the tail and tongue arrangement shown. The bolts 50 being pivoted to one of the clamp members 27 are also retained in place. When removing the clamp 15, the nuts 58 70 are loosened, and the bolts 50 are swung outwardly, as indicated by an arrow 65 of Fig. 2, from the slots 57, thus leaving the clamp members 27 free to swing outwardly and easy to remove from the polish rod 11. 75 The parts of the clamp are few and are very rugged in construction so that they are capable of withstanding the great forces applied to the polish rod, due to the novel leverage arrangements of the construction. 80

I claim as my invention:

1. In a device of the class described, the combination of: a pair of hinged clamp members providing a channel; a pair of faces, one of said faces being formed on each of said clamp members adjacent to their point of hinging; a gripper operated by the closing of said clamp members for forcing a member against said faces to clamp said member against movement; means for supporting said gripper in said channel; and means for forcing said clamp members together to operate said gripper and for retaining said members in closed position. 95

2. In a device of the class described, the combination of: a pair of hinged clamp members; a pair of faces, one of said faces being formed on each of said clamp members adjacent to their point of hinging; a gripper operated by the closing of said clamp members for forcing a member against said faces to clamp said member against movement; means for attaching said gripper to one of said clamp members, but allowing relative movement; and means for forcing said clamp members together to operate said gripper and for retaining said members in closed position. 100

3. In a device of the class described, the combination of: a pair of cooperating clamp members providing a channel, said channel being arranged for the extension of a rod therethrough; a gripper adapted to engage and force said rod into non-movable engagement with the bottom of said channel, said gripper having wedge faces; means for supporting said gripper in said channel; and convex engagement formations provided on said clamp members adapted to engage and force said gripper into gripping engagement with said rod. 115

4. In a device of the class described, the combination of: a pair of hinged clamp members providing a channel, said channel being arranged for the extension of a rod therethrough; a gripper engaged by both of said clamp members and operated by the closing thereof for retaining said rod securely in said channel; means for support- 120 125 130

ing said gripper in said channel; and means for forcing said clamp members together to operate said gripper and for retaining said members in closed position.

5. In a device of the class described, the combination of: a pair of hinged clamp members providing a channel, said channel being arranged for the extension of a rod therethrough; a gripper for retaining said rod securely in said channel, said gripper being forced into gripping engagement with said rod by said pair of clamp members; means for supporting said gripper in said channel; and means for forcing said clamp members together to operate said gripper and for retaining said members in closed position.

6. In a device of the class described, the combination of: a pair of hinged clamp members providing a channel, said channel being arranged for the extension of a rod therethrough; a gripper adapted to engage and force said rod into non-movable engagement with the bottom of said channel, said gripper having wedge faces; means for supporting said gripper in said channel, and engagement formations provided on said clamp members adapted to engage and force said gripper into gripping engagement with said rod.

7. In a device of the class described, the combination of: a pair of cooperating clamp members providing a channel, said channel being arranged for the extension of a rod therethrough; a gripper adapted to engage and force said rod into non-movable engagement with the bottom of said channel, said gripper having wedge faces; engagement formations provided on said clamp members adapted to engage and force said gripper into gripping engagement with said rod; means for supporting said gripper in said channel, and means for moving said clamp members in such a manner as to cause said formations to move said gripper.

8. In a device of the class described, the combination of: a pair of hinged clamp members providing a channel, said channel

being arranged for the extension of a rod therethrough; a gripper adapted to engage and force said rod into non-movable engagement with the bottom of said channel, said gripper having wedge faces; engagement formations provided on said clamp members adapted to engage and force said gripper into gripping engagement with said rod; means for supporting said gripper in said channel, and means for moving said clamp members in such a manner as to cause said formations to move said gripper.

9. In a clamp of the class described, the combination of: a pair of clamp members hinged together, said clamp members co-operating to provide a channel; an engagement formation formed on each of said clamp members in said channel; a gripper disposed in said channel, said gripper having wedge faces adapted to be engaged by said engagement formations; means for retaining said gripper movably in said channel; and means for hingeably moving said clamp members in order to cause said engagement formations to move said gripper in said channel.

10. In a clamp of the class described, the combination of: a pair of clamp members hinged together, said clamp members co-operating to provide a channel; an engagement formation formed on each of said clamp members in said channel; a gripper disposed in said channel, said gripper having wedge faces adapted to be engaged by said engagement formations; a tail formed on said gripper having an opening formed in said tail; a tongue extending from one of said clamp members through said opening, thus tying said gripper to one of said clamp members, but permitting a relative movement therebetween; and means for hingeably moving said clamp members in order to cause said engagement formations to move said gripper in said channel.

In testimony whereof, I have hereunto set my hand at Los Angeles, California, this 29th day of January, 1925.

MARTIN MADSEN.
